(57) CLAIM

The ornamental design for a table base, as shown and described.

DESCRIPTION

FIG. 1 is a perspective view of the table base of my design;
FIG. 2 is a top view of the table base;
FIG. 3 is a front view of the table base, (the back side view, being a mirror image of the front view, is not shown);
FIG. 4 is a right side view of the table base;
FIG. 5 is a left side view of the table base; and,
FIG. 6 is a bottom view of the table base.
